UNITED STATES PATENT OFFICE.

CHARLES S. HARRIS, OF MILWAUKEE, WISCONSIN, ASSIGNOR OF ONE-THIRD TO THOMAS E. SELLEN AND ONE-THIRD TO ADOLPH H. CHROMASTA, BOTH OF MILWAUKEE, WISCONSIN.

REGULATOR FOR GAS-STOVES.

987,458.

Specification of Letters Patent. Patented Mar. 21, 1911.

Application filed May 24, 1910. Serial No. 563,170.

To all whom it may concern:

Be it known that I, CHARLES S. HARRIS, a citizen of the United States, residing at Milwaukee, in the county of Milwaukee and State of Wisconsin, have invented new and useful Improvements in Regulators for Gas-Stoves, of which the following is a specification.

This invention relates to controllers for the burners of gas stoves, the object being to provide simple and effective means for letting on the full flow of gas when a cooking vessel or other object to be heated is placed in position and reducing or cutting off the flow of gas when the vessel or object is removed, thus preventing the needless waste of gas when the burner is temporarily out of use and a full flow of gas is not required.

20 A further object of the invention is to provide a simple and effective means for maintaining a reduced flame so as to avoid the necessity of frequently relighting the burner when the same is thrown into and out of 25 operation at comparatively short intervals.

The invention consists of the features of construction, combination and arrangement of parts hereinafter fully described and claimed, reference being had to the accompanying drawings, in which:—

Figure 1 is a sectional elevation of a gas stove embodying my invention. Fig. 2 is a vertical transverse section on line 2—2 of Fig. 1. Fig. 3 is a horizontal section taken 35 substantially on line 3—3 of Fig. 1.

Referring to the drawings, 1 designates a portion of a gas stove or range of any suitable construction, which may be provided with any desired number of pot-holes and 40 burners; but as they are all alike in construction, the illustration and description are limited to a single pot-hole and burner.

2 designates the pot-hole, 3 the grid or grating which supports the cooking vessel 45 in position and 4 the burner arranged below the grid. The burner is in communication with a mixing tube 5 having the usual air inlet 6, into which extends a gas supply fixture or pipe 7 leading from a gas service 50 pipe, said pipe or fixture 7 being provided with the usual nipple 8 through which the gas discharges into the mixing tube. In the pipe or fixture 7 is arranged a stop cock 9 for cutting off or regulating the flow of gas,

which cock is mounted to turn in a casing 55 10 into which the pipe or fixture 7 extends, or which forms a part of the said fixture.

Arranged for vertical movement in the pot-hole 2 is a depressible controller comprising a pusher head 11 mounted upon the 60 upper end of a stem 12 slidable through a guide tube 13. This tube 13 is disposed in the central opening 14 of the annular burner 4 and extends through a perforation in a supporting bar 15 carried by the burner. 65 Above the bar the tube is formed with a shoulder 16 to rest thereon, and the lower end of the tube is threaded, as at 17, to receive a clamping nut 18 adapted to bear against the underside of the bar to draw the 70 shoulder into clamping engagement with the upper surface of the bar, whereby the tube is detachably secured in position.

The lower end of the stem 12 is provided with a fork or saddle 19 having a friction 75 roller 20 journaled therein. This fork or saddle straddles the normal approximately horizontal arm of a bell crank lever 21 which is engaged by the friction roller, the other or normally substantially vertical arm of 80 the said lever being provided with a longitudinal series of perforations 22. When a cooking vessel is placed in position upon the grid and above the pot-hole, it comes in contact with the depressible head 11 and forces 85 the latter down flush with the top of the stove, thereby communicating motion to the bell crank lever 21. Upon the removal of the pot or vessel, the parts described are returned to their normal position by means 90 hereinafter specified, the friction roller 20 providing for the easy relative play between the saddle and bell crank lever to allow the same to have unrestricted movement without binding upon one another. 95

Arranged within the supply pipe or fixture 7 is a controlling valve comprising a tapered plug 23 extending horizontally and transversely through the valve casing 10, the reduced end of the said valve being 100 threaded to receive a clamping nut or screw and washer 24 whereby it is held from displacement. That portion of the valve which passes through the casing 10 is formed with a transverse feed port 25, with which communicates a feed groove 26. When the parts are in the normal position as above described, the port 25 extends vertically and is closed

by the upper and lower walls of the casing 10 to prevent the passage of gas to the burner. A tube 27 extends from the casing 10 to the top of the burner 4, and is provided at its end adjacent said burner with a burner tip or pilot burner 28, the end of the tube fitted in the casing 12 at all times registering with the groove 26 irrespective of the position of the valve 23, so that there 10 is a constant supply of gas to said tube in order to enable the pilot light to be kept constantly burning.

The larger end of the valve 23 carries a depending lever arm 29 provided with a longitudinal series of openings 30. This arm 29 is connected with the depending arm of the bell crank lever 21 by a connecting rod or link 31 secured at its opposite ends respectively to the bell crank lever and valve 20 arm by pivot screws or bolts 32 and 33 passing through any one of the series of openings in the respective lever arms. The connecting rod or link is thus adjustably connected to the lever and lever arm so that a 25 degree of motion imparted to the valve 21 under prescribed degree of movement of the depressible member 11 may be regulated to either entirely cut off the supply of gas to the burner when the vessel is removed and 30 the depressible element is in normal position, or to reduce the flow of gas to any desired extent to leave just enough gas burning at the burner outlet to avoid the necessity of lighting the burner each time a pot or vessel 35 is placed in position. A coil spring 34 surrounds the enlarged end of the controlling valve and is fixed at one end to the casing 10 and at the opposite end to the lever arm 9. This spring is tensioned by the 40 opening movement of the valve when the depressible element is depressed, so that when the weight of the pot or vessel is removed from said element the spring will react and close the valve and restore the operating 45 parts to normal position.

A needle valve or regulating screw 35 extends at an angle through the casing and into the valve 23 with its tapered end arranged to control the feed of gas from the 50 groove 26 to the adjacent end of the tube 27, whereby the amount of gas supplied to the pilot burner may be conveniently regulated.

From the foregoing description, taken in connection with the drawings, the construction 55 and mode of operation of my improved gas stove regulator will be readily understood, and it will be apparent that after the pilot burner 28 is lighted the burner will be primed for operation so that when the pot 60 or vessel is placed in position the weight of the same will depress the head 11 and effect the opening of the valve 23 for the supply of gas, which will be lighted by the flame from the burner 28. When the vessel is removed the valve will be adjusted to entirely

cut off the flow of gas leaving only the pilot burner lighted, or to reduce the flow of gas to a desired degree to leave the burner 4 burning low, so that the necessity of relighting the same will be obviated. When it is 70 desired at all times to supply a small amount of gas to the burner 4, while the parts are in normal position, the pilot burner may be dispensed with.

It will be understood, of course, that the 75 invention is of value in saving the necessity of the burning of gas when the burner is not in use and saving of time in relighting; a very important feature especially in restaurants, lunch houses, boarding houses, etc., 80 where cooking utensils are constantly being applied to and removed from the burner.

Having thus described the invention, what I claim as new, is:—

1. In a regulator of the character described, the combination of a burner having a central opening provided with a horizontal partition formed with a threaded opening therein, a guide tube provided at its base with a shoulder resting on said partition and 90 a threaded stem engaging said threaded opening and projecting below the partition, a clamping nut engaging said stem, a depressible element provided with a stem extending through and slidably mounted in, 95 said guide tube, said stem being provided at its lower end with a fork, a friction roller adjustably mounted for rotation in said fork, a bell crank lever having one of its arms extending through the fork, and engaged by said friction roller, a rotary valve controlling the flow of gas to the burner, a lever arm connected with the valve, and a link connecting said lever arm with the other arm of the bell crank lever. 100

2. In a regulator of the character described, the combination of a burner, a guide tube carried by the burner, a depressible element having a stem slidably mounted in and projecting below said guide tube, said element having, at its lower end, a fork, a friction roller journaled for rotation in the arms of the fork and adjustable to different elevations therein, a bell crank lever having one of its arms extending through the fork 115 and engaging said friction roller, a rotary valve governing the flow of gas to the burner, a lever arm connected with said valve, a spring for normally holding the valve in closed position, and a link adjustably connected at one end with one arm of the bell crank lever and at its opposite end with the said lever arm. 120

3. In a regulator of the character described, the combination of a burner having a source of gas supply, a depressible element slidably mounted on the burner, a valve casting having a passage for the flow of gas to the burner, a horizontally disposed transversely extending rotary valve having a port 125 130

for communication with said passage and provided in its periphery with a segmental groove intersecting one end of said port, a spring for normally holding the valve closed, a pilot burner tube connected with the valve casing and always in communication with the passage therein through said segmental groove, a set screw mounted upon the casing and having a tapered end to enter the groove, a lever arm connected with the valve, a bell crank lever having one of its arms engaging said depressible element, and a link adjustably connected at one end with the other arm of the bell crank lever and at its opposite end with the lever arm. 15

In testimony whereof I affix my signature in presence of two witnesses.

CHARLES S. HARRIS.
